Specification for Design.

Patented Oct. 5, 1920.

Application filed June 26, 1917. Serial No. 177,138. Term of patent 3½ years.

To all whom it may concern:

Be it known that I, CLAUDIA I. PILLING, a citizen of the United States, residing in the city and county of Denver and State of Colorado, have invented a certain new, original, and ornamental Design for a Lady's Undergarment, of which the following is a specification, reference being had to the accompanying drawing, forming a part hereof.

In the drawing, Figure 1 is a perspective view of the undergarment showing my new design; and Fig. 2 is a view thereof showing the undergarment spread open.

Having thus described my invention, I claim:—

The ornamental design for a lady's undergarment, as shown.

CLAUDIA I. PILLING.
